DUAL SPEED INTERVAL TIMER

William P. Gallagher, Chicago, Ill., assignor to
 International Register Company, Chicago, Ill.,
 a corporation of Illinois

Application February 26, 1951, Serial No. 212,737

23 Claims. (Cl. 161—15)

1

This invention relates to timing mechanisms, more particularly to the kind for actuating an alarm and/or a switch after a predetermined interval of time.

In the laboratory, factory, shop, and home there are many operations that have to be carefully timed; that is, they have to be terminated after a predetermined period. Some have to run for a few minutes, others for many minutes. For many such operations the duration has to be reasonably exact regardless of whether the period of operation be very brief or fairly long. Moreover, for some operations the starting and stopping has to be automatic, or the starting effected manually and the stopping automatically. In many such instances, mechanisms such as switches can be operated to initiate and terminate the operation or to merely terminate the operation. For other operations, the starting and stopping has to be effected manually. In the latter instance, the one in charge of the operation may find it necessary to be busy with other matters. Some of these perhaps might be related to the timed operation, others possibly not so related. In any case, attention momentarily may become so completely absorbed in the other matter as to make the attendant oblivious of the passing of the time for terminating the main operation, unless there is some kind of signal actuated to indicate the expiration of the timed operation.

Present practice involves the use of timing devices generally known as "interval timers" which usually are manually set in motion when initiating a certain operation. These interval timers, upon the completion of the timed period, operate or actuate a signal—visual or audible—after the elapse of the predetermined time for which the device is manually set. When such devices have heretofore been constructed for accurate operation for short intervals, they could not be used effectively for measuring comparatively long intervals of time. On the other hand, devices heretofore constructed for general use in measuring a fairly long interval of time as a rule could not be used for accurately measuring a comparatively short time interval.

The main objects of this invention, are to provide an improved form of interval timer which may be set for accurately measuring time periods of comparatively short duration, as well as time periods of comparatively long duration; to provide improved means for connecting a rotatable time-measuring indicator to a motor so as to vary the relative speed of rotation of said

2

indicator during predetermined portions of its revolution; to provide an improved arrangement of a dial associated with such a time-measuring indicator having within its circumference the markings of both the short and long time periods; to provide manually-actuatable means for setting said time-measuring indicator in operative relationship with a constantly operating motor; to provide improved means for holding said time-measuring indicator from operative relationship with said motor during the setting of the time indicator; to provide an improved signal means associated with said time-measuring indicator; and to provide an improved dual-speed interval timer of this kind which has the minimum of parts, hence economical to manufacture, simple to operate, and accurate in functioning.

In the accompanying drawings:

20 Fig. 1 is a front elevational of a presently preferred form of interval timer embodying this invention, to which is juxtaposed a positioning pointer on a surrounding housing;

25 Fig. 2 is an exploded view of the working parts of this improved device;

Fig. 3 is a rear elevation of the embodiment shown in Fig. 1;

30 Fig. 4 is a side elevation of the same, as viewed in the direction of the arrow shown in Fig. 3, the housing for the dual-speed gearing being shown in section;

35 Fig. 5 is a front elevation, as viewed from the plane of the line 5—5 of Fig. 4, the uppermost driven gear being broken away to more clearly indicate the one point of common meshing of the two driven gears;

Fig. 6 is an opposed side elevation of the same, the dual-speed gear housing being in section;

Fig. 7 is a rear view of the same taken on the 40 line 7—7 of Fig. 6;

Fig. 8 is a face view of the two integrated driven gears, the view being just the reverse of that shown in Fig. 5;

Fig. 9 is a cross sectional view of the integrated 45 driven gears and the vibrator-control cam as mounted on the time-indicator shaft;

Fig. 10 is an exploded perspective of the two driven gears; and

Figs. 11, 12 and 13 are enlarged fragmentary 50 details illustrative of the gear tooth formation of the two driving gears and the two driven gears, respectively.

The distinctive concept of this invention involves an arrangement of gears between a motor and a rotatable, time-measuring indicator which

gears may be selectively set in driving relationship so as to cause the rotation of said time-measuring indicator at different speeds for successive portions of a nearly 360 degree revolution of the indicator.

Referring first to Figure 2, the preferred embodiment of this invention comprises a manually-adjustable time-measuring indicator A, and two-speed driven gearing B which may be selectively meshed with motor-driven driving gearing C so as to cause the time-measuring indicator to revolve at two different speeds during its revolution, and at the end of which revolution cam means D effects the release of a signal means E.

The time-measuring indicator A comprises a shaft 15 having its inner end journaled in the mounting flange 38' of a bracket 38, this shaft being manually rotatable in one direction for setting in meshing engagement the gearing B and C, whereupon said shaft will be revolved in the reverse direction by the motor 17. The journaled mounting of this inner end of the shaft 15 in the mounting flange 38' has sufficient looseness or tolerance to permit the outer portion of the shaft to be cocked or tilted laterally a very small amount to facilitate the speed change from one gear diameter to another gear diameter, as will later appear. The time-measuring indicator A also comprises a finger knob 18 and a dial 19 associated with the shaft 15 to permit an indicated amount of rotation required to effect the operation of the signal means E after a predetermined lapse of time.

The shaft 15 has secured thereto a bushing 20 (see Fig. 9) grooved at 21 for seating in the bottom of a slot or recess 33 in the plate 27 as will be later described. The bushing 20 also affords a support for the gearing B. Also fixed on the shaft 15 is the cam D axially spaced from the bushing 20. At its outer end the shaft 15 is formed with an enlargement 22 which is cut away at 23 and slotted at 24 to form a resilient or compressible hub 25 over which the dial 19 is adapted to be pushed in a snug push fit to secure the dial to the shaft in proper angular relationship to correspond with the angular position of the gearing B. The dial has a non-circular bore having a flat spot engaging with the flat spot 23.

The mounting 16 comprises a pair of oppositely depressed plates 26 and 27 secured together by fastening means 28 to provide enclosures respectively for the gearing B and C and the gearing (not herein shown) which connects the gearing C with the motor 17.

The plate 26 mounts a threaded hub 29 wherein is adapted to be screwed a nut 29a for the purpose of attaching the device to a suitable part of a supporting frame 39' (see Fig. 4). Lugs or shoulders 30, 31 and 32 are punched laterally from the face of the depressed part of the plate 26. The former of these two lugs 30 and 31 are punched outwardly to coat with slots in the aforesaid frame part to insure proper positioning of the device on the frame. The latter of these lugs, namely, 32, is punched inwardly to coat with a similar lug or shoulder 49 on the gearing B to limit the opposite rotation of the shaft 15.

As previously described, the plate 27 is formed with a slot or recess 33 for receiving the journal bushing 20, on the shaft 15, to permit a sidewise or radial deflection of this intermediate portion of the shaft with respect to the mounting plate 27. The shaft has a sufficient looseness in the hub 29 of outer cover plate 26 to permit the slight angular cocking of the shaft. A spring 34

secured on and between lugs 35 and 36, struck out from the plate 27, normally urges the bushing 20 against the bottom of the recess 33 whereby the shaft 15 is properly positioned to normally mesh the gearing B with the gearing C to effect the proper limited rotation of the shaft 15, as will be explained more fully presently. The plate 27 also provides support for the motor 17 which is a conventional, synchronous-type motor suitably geared to a shaft 37 (see Fig. 2) whereto is attached the gearing C. The plate 27 also has secured thereto, at one side of the motor 17 and adjacent the cam D, a bracket 38 which forms a part of the signal means E, to be explained presently.

The finger knob 18 and the time dial 19 may be secured together in any suitable manner so that they turn as a unit. When the shaft 15 is in its neutral or starting position, the "O" on the dial 19 registers with the pointer 39 suitably formed on some surrounding part of the supporting frame 39' whereon this interval timer is to be mounted.

Because of the variable speeds at which the shaft 15 is to operate by the meshing of the gearing B and C presently to be described, the circumferential portion of the dial 19 is divided by markings and numerals into two portions. For a substantial part of its circumference, the dial is scored and numbered to represent equal time units, each of 15 minutes duration. Another portion of the dial circumference is scored to represent 15 equal units of time, each of 1 minute duration, the first ten of these one minute intervals being numbered 1 to 10. It of course will be understood that the point of dividing the dial 19 into the respective parts and the length of the timing periods are not critical to this disclosure. The arrangement of these will be dependent upon the requirements for which the timer is constructed.

The gearing B comprises sector-shaped gears 40 and 41 of different diameters concentrically attached to the bushing 20 on the shaft 15. These gears are adapted to successively mesh with the gear 42 and pinion 43 which constitute the gearing C, to effect the fast and slow rotation respectively of the shaft 15 (with its attached knob and dial 18 and 19) for the predetermined portions of its rotation.

The gear 40, as herein shown (see Fig. 8), is of a circumference slightly more than 180 degrees whereas the gear 41 is of a circumference slightly less than 180 degrees. Each gear 40 and 41 is formed with an axial recess 44 to fit over a hub 45 on the bushing 20 and permit the required disposition thereof in the proper angular relationship to insure their successive and proper meshing with the gearing C. In the gear 41 the recess is non-circular to fit the non-circular hub 45. The gears 40 and 41 are preferably spaced apart axially a short distance by punching a spacing cup formation 48 rearwardly from the web of the large gear 40, or by providing spacing washers between the gears. To secure these two gears 40 and 41 in their proper angular relationship, the gear 40 is formed with a tongue 46 which fits in a recess 47 in the gear 41 when the gears are superimposed upon each other. These gears are staked to the bushing 20 in the conventional manner in mechanism of this kind.

As will be noted from Figs. 5 and 8, the relative angular disposition of the gears 40 and 41 is such that one radial terminus of the gear 40 slightly overlaps the adjacent or corresponding radial

terminus of the gear 41 whereas there is a circumferential gap between the other radial termini of these gears. This radial overlapping insures a successive meshing of the gear 40 with the gear 42 as the gear 41 passes out of meshing engagement with the pinion 43 during the normal rotation of these gears by the motor 17. The radial gap between the termini of these gears 40 and 41 constitutes an angularly extending idling gap indicated at *g* in Figure 8 to provide for an idling freedom of continued rotation of the motor-driven gear 42 and pinion 43 when the shaft 15 has returned to its starting position. The gear 41 has a lug 49 struck out from the face thereof to coact with the lug 32 on the mounting plate 26 for limiting the opposite rotation of the shaft 15.

The motor driven gearing C, as already noted, is in the form of a coaxially-arranged, integral gear 42 and pinion 43 connected to the motor-driven shaft 37 so as to rotate at the predetermined speed.

It will be seen from the foregoing that the motor 17 is geared to produce almost a complete revolution of the shaft 15 in approximately 85 minutes, and because of this extremely slow speed of rotation it is desirable that the teeth on the gearing B and C, be of very small tooth size, as shown in magnified form Figs. 11, 12 and 13. Moreover, the very small tooth size and the form of the teeth is important for securing an effective continuity of operation of the shaft 15 as the driving transfer is made from the gear 41 to the gear 40. For the motor-driven gears 42 and 43 and the gear 41 the teeth are preferably sharp or pointedly triangular like saw teeth, but the slope of the teeth on gear 41 is more gradual than on the gears 42 and 43 (see Figs. 11 and 12). However, the teeth on the gear 40 are rounded off, taking the form of a scallop (see Fig. 13).

The cam means D, which controls the retraction and release of the signal means E, is in the form of a disk 50 fixed on the shaft 15 in axially spaced relationship to the shaft bushing 20. The disk 50 is formed with an internal annular cam track 51 terminating in adjacent, oppositely-disposed, radial offsets 52 and 53, which offsets coact with a cam track follower 54 for effecting the desired operation of the signal means E. As most clearly shown in Fig. 8, the offset 52 is in the nature of an outwardly-extending depression or recess, whereas the offset 53 is in the form of an inwardly-extending shoulder.

The signal means E herein-shown comprises the bracket 38 whereon is formed a vibrator 55 to which is attached an armature 56. The action of this vibrator is controlled by an arm 57 on which is mounted the cam-track follower 54.

The bracket 38, somewhat in the form of a broad U-shaped member, is suitably welded, soldered or otherwise secured to the mounting plate 27, at one side of the motor 17, so as to dispose the vibrator 55 with the attached armature projecting into the field of the motor 17 so as to be acted upon magnetically by the motor field. As previously described the lateral flange 38' of bracket 38 provides a bearing for the inner end of the shaft 15.

The vibrator 55 is herein-shown integral with the bracket 38, being formed by cutting out bordering portions of the base of the U-shaped bracket. The end of the armature 56 is riveted to the vibrator 55 adjacent its outer end. A tempered steel spring extension 58 is secured to the end of the vibrator 55 to dispose the end of the

extension for engagement by the control arm 57.

The control arm 57 has one end recessed at 59 and shouldered at 60 (see Fig. 2) to permit the arm to be releasably set in the slot 61 in one of the transverse legs of the U-shaped part of the bracket 38. Such a mounting permits a limited rocking of the arm 57 under the oppositely acting forces of a spring 62 and the cam track follower 54 as the latter is influenced by the cam track 51 of the cam D.

When the aforesaid recessed and shouldered end of the arm 57 is seated in the bracket slot 61, the arm 57 is positioned to shiftably set the outer free end thereof in a slot 63 (see Fig. 3) in the other transverse leg of the U-shaped bracket 38. A longitudinally-spaced tongue 64 and lug 65 on the arm 57 are thereby located on opposite sides of the aforesaid bracket leg. The tongue 64 is positioned to engage and depress the spring extension 58 of the vibrator 55 and immobilize the vibrator when the cam-track follower 54 is engaged by the cam track 51 on the cam "D." The lug 65 is positioned to retain the spring 62 in position to normally retract the arm 57 to hold the cam-track follower 54 in constant contact with the aforesaid cam track 51.

This arrangement of the arm 57, so as to be depressed by the coaction of the cam track 51 and the follower 54, thereby forces and holds the tongue 64 against the spring extension 58 and insures an effective silencing of the vibrator 55, so long as the cam-track follower 54 is in contact with the cam track 51.

It should be understood that although the cam-actuated arm 57 is herein used to immobilize a magnetic vibrator, the arm 57 could be employed with equal facility to actuate a switch that would close a circuit to some other type of signal—visual or audible—or for still some other purpose.

The operation of the herein-shown embodiment of this invention is substantially as follows:

The motor 17 is connected in an electric circuit and normally is running constantly, unless a switch in that circuit is open.

The dial 19 is normally set at the "off" position when the timer is not in use. The dial is so positioned for the reason that, in order to maintain the tongue 64 on the arm 57 of the signal control means E in position to silence the vibrator 55, the dial 19 has to be turned to shift the cam-track follower 54 out of the offset depression 52 and over the offset shoulder 53 into contact with the cam track 51. No further counterclockwise movement of the dial 19 is permissible by reason of the contact of the lug 49 on the gear 41 with the lug 32 on the mounting plate 26. In such position the driven gears 40 and 41 are free of contact with the motor-driven driving gears 42 and 43.

When one desires to make use of this timer to operate a signal (or close a switch or actuate some other device) at the end of a given period of time within the range of the dial 19, the knob 18 is grasped by the fingers and thumb and turned clockwise. This moves the cam D to disengage the follower 54 from behind the offset shoulder 53 and into the offset depression 52. Instantly, the spring 65 thereupon shifts the arm 57 to retract the tongue 64 and momentarily frees the action of the vibrator 55 under the influence of the armature 56. The sounding of the vibrator at that moment is assurance that it is in operative condition to effect the desired warning at the end of the time period for which the device is to be set.

70

In this preliminary turning of the dial clockwise, and in the continuing turning thereof for its setting, the thumb and finger engagement on the knob 18 tends to depress the shaft 15 slightly radially in the recess 33 against the action of the spring 34. This will sufficiently enlarge the normal radial distance between the shaft 15 and the axis of the gearing C to maintain the gearing, B and C out of mesh and thereby avoid any grating or chattering of the gearing during this clockwise rotation of the dial 19. However, the sloping and rounded form of the extremely fine gear teeth on the driving and driven gears permits relative slippage therebetween in this preliminary setting operation, by the action of the teeth camming the shaft 15 sidewise even if the knob 18 is not pushed downwardly.

The dial 19 is turned clockwise to a position to register with the pointer 39, the dial marking corresponding with the number of minutes following which it is desired to have the signal sound.

The limit of such clockwise turning of the dial 19, and of course the shaft 15, is the engagement of the lug 49 on the gear 41 with the lug 32 on the mounting plate 26. The engagement of these lugs is by opposite faces from those which limit the counterclockwise movement of the dial 19 previously noted.

The instant the cam-track follower 54 is moved out of the cam-track depression 52 the arm 57 is shifted to immobilize the vibrator 55.

When the desired marking on the dial 19 is brought into registration with the pointer 39, the knob 18 is released. Thereupon the spring 34 presses the shaft bushing 20 into the base of the recess 33 and meshes one or the other of the sector-shaped driven gears 40 and 41 with the driving gear 42 or the driving pinion 43. If the setting has been within the 15-minute period shown on the dial 19 the gear 40 meshes with the gear 42. If the setting has been beyond the 15-minute marking on the dial 19 the gear 41 is meshed with the pinion 43. During the reverse counterclockwise rotation from this latter setting, the gear 40 comes into mesh with the gear 42 as the gear 41 moves out of meshing engagement with the pinion 43 (see Fig. 5).

Once the knob 18 has been thus turned to mesh the gearing B and C, the motor 17 begins to drive the shaft 15 in a counterclockwise direction. During the time that the gear 41 is in mesh with the pinion 43 the shaft 15 is rotating comparatively slow, at the rate of approximately 70 minutes for a little less than 180 degrees. However, during the time the gear 40 is in mesh with the gear 42 the shaft 15 is rotating at a much faster speed, approximately 180 degrees in 15 minutes, i. e., several times as fast as when the gear 41 meshes with the pinion 43.

It should be explained that the sum of the radii of the gear 40 and the gear 42 is about .011 of an inch less than the sum of the radii of the gear 41 and the pinion 43. Therefore, when the shaft 15 is turned to "set" the timer for more than a fifteen minute run, the entering or retreating engagement of the gear 41 with the pinion 43 (during the opposite rotations of the shaft 15) spaces the axis of the shaft 15 from the axis of the motor-driven shaft 37 sufficiently to avoid any momentary scraping of the gears 40 and 42 as the gear 41 and pinion 43 move into and out of mesh.

During the revolution of the shaft 15 by the motor 17, the cam-track follower 54, contacting

the cam track 51, depresses the arm 57 to hold the tongue 64 against the spring extension 58 so as to prevent the operation of the vibrator 55. As soon as the follower 54 drops into the offset depression 52 on the cam D (see Fig. 8), the O on the dial 19 meanwhile reaching the pointer 39, the spring 66 shifts the arm 57 to retract the tongue 64 and free the vibrator 55 to sound. The vibrator will continue to sound until the dial 19 is turned for a resetting, or is shifted (counterclockwise) so as to move the cam-track follower 54 up over the shoulder 53 onto the cam track 51.

Variations and modifications in the details of the structure and arrangement of the parts may be resorted to within the spirit and coverage of the appended claims.

I claim:

1. An interval timer comprising, a motor, a time-measuring device having rotary movement, multiple speed means for connecting said time-measuring device with said motor comprising driving gearing connected with said motor; a plurality of circular sector-shaped driven gears of different diameters connected to said time measuring device, and means for establishing different meshing relations between said driven gears and said driving gearing for operating said device at variable speeds during predetermined portions of its rotary movement.

2. An interval timer comprising, a motor, a time-measuring device having rotary movement, multiple speed means for connecting said time-measuring device with said motor comprising driving gears connected with said motor, a plurality of concentrically mounted circular sector-shaped driven gears of different diameters connected to said time-measuring device, and manually operated means for establishing different meshing relations between said driving and driven gears for operating said device at variable speeds during predetermined portions of a 360 degree revolution.

3. An interval timer comprising, motor-driven gearing, a time-measuring indicator, a pair of concentrically mounted circular sector-shaped driven gears of differing diameters movable into and out of mesh with said motor driven gearing to rotate said indicator, and manual means for meshing either one of said circular driven gears with said motor-driven gearing so as to effect the operation of said indicator at variable speeds during predetermined portions of its revolution.

4. An interval timer comprising, a mounting, 55 motor-driven continuously rotating gearing journaled on said mounting, a time-measuring indicator journaled on said mounting, a pair of concentrically mounted circular sector-shaped driven gears of differing diameters movable into and out of mesh with said motor driven gearing for rotatably connecting said indicator with said gearing, manual means for meshing either one of said gears with said gearing so as to effect the operation of said indicator at variable speeds 60 during predetermined portions of its revolution, and coacting shoulders associated with said mounting and said indicator for limiting the opposite rotation of said indicator to approximately 360 degrees.

5. An interval timer comprising, motor-driven continuously rotating driving gearing, a time-measuring indicator, a pair of circumferentially spaced, concentrically-arranged sector-shaped gears of differing diameters connectable to rotate said indicator, the circumferential spacing be-

tween adjacent ends of said sector-shaped gears defining an idling gap in which said driving gearing is adapted to have idling rotation, and manual means for meshing said gears with said motor-driven gearing so as to effect the operation of said indicator at variable speeds during predetermined portions of its revolution.

6. An interval timer comprising, a mounting, motor-driven continuously rotating driving gearing journaled on said mounting, a time-measuring indicator journaled on said mounting, a pair of circumferentially-spaced concentrically-arranged sector shaped driven gears of differing diameters for rotatably connecting said indicator to said gearing, the circumferential spacing between two adjacent ends of said sector-shaped driven gears defining an angular idling gap in which said driving gearing normally has idling rotation, manual means for meshing said gears with said gearing so as to effect the operation of said indicator at variable speeds during predetermined portions of its revolution, and coacting shoulders on said mounting and one of said gears adapted to limit the opposite rotation of said indicator to approximately 360 degrees.

7. An interval timer comprising, a mounting, a plurality of concentrically mounted motor operated driving gears journaled on said mounting, a radially-deflectable shaft journaled on said mounting, a plurality of concentrically mounted driven gears of differing diameters on said shaft adapted to successively mesh with said motor operated driving gears, and means for manually effecting a radial deflection of said shaft to momentarily disengage said driving and driven gears to permit a rotation of said shaft to so set the engagement of one of said gears with said gearing as to predetermine the degree and speed of rotation of said shaft by said motor-driven gearing, certain of said gears having rounded teeth to permit forced slippage of said gears.

8. An interval timer comprising, a mounting, motor-driven continuously rotating driving gearing journaled on said mounting, a radially-deflectable shaft journaled on said mounting, a pair of circumferentially-spaced concentrically-arranged sector-shaped driven gears of differing diameters fixed on said shaft and adapted to successively mesh with said motor-driven gearing, the circumferential spacing between adjacent ends of said sector-shaped driven gears defining an angularly extending idling gap in which said continuously rotating driving gearing normally has idling rotation and means for manually effecting a radial deflection of said shaft to momentarily hold said sector-shaped driven gears from engaging with said driving gearing while effecting a reverse rotation of said shaft to so set the engagement of one of said gears with said motor-driven gearing as to predetermine the degree and speed of rotation of said shaft by said motor-driven gearing.

9. An interval timer comprising, a mounting, motor-driven gearing journaled on said mounting, a shaft journaled on said mounting, said mounting being recessed adjacent the journal of said shaft to permit said shaft to be radially deflected, gears of differing diameters on said shaft adapted to successively mesh with said motor-driven gearing, and means for manually effecting a radial deflection of said shaft to momentarily disengage said gears to permit a rotation of said shaft to so set the engagement of one of said gears with said gearing as to pre-

determine the degree and speed of rotation of said shaft by said motor-driven gearing.

10. An interval timer comprising, a mounting, motor-driven gearing journaled on said mounting, a shaft journaled on said mounting, said mounting being recessed adjacent the journal of said shaft to permit said shaft to be radially deflected, gears of differing diameters on said shaft adapted to successively mesh with said motor-driven gearing, resilient means normally urging said shaft into an axial position to maintain the meshing of said gears and gearing, and means for manually effecting a radial deflection of said shaft to momentarily disengage said gears to permit a rotation of said shaft to so set the engagement of one of said gears with said gearing as to predetermine the degree and speed of rotation of said shaft by said motor-driven gearing.

11. An interval timer comprising, a mounting, a motor, a time-measuring indicator journaled on said mounting for rotation through nearly a complete revolution from a starting position, multiple-speed gearing for connecting said indicator to said motor for operating said indicator at variable speeds for predetermined portions of its revolution, manual means for turning said indicator away from said starting position to set said gearing for effecting the desired operation of said indicator, a device controlling arm, and a cam rotatively synchronized with said indicator to hold said arm in a retracted position when said indicator is rotated away from its starting position but release said arm when said indicator is in its starting position.

12. An interval timer comprising, a mounting, a motor, a time-measuring indicator journaled on said mounting for rotation through nearly a complete revolution from a starting position, multiple-speed gearing for connecting said indicator to said motor for operating said indicator at variable speeds for predetermined portions of its revolution, manual means for turning said indicator away from said starting position to set said gearing for effecting the desired operation of said indicator, a device controlling arm, a cam rotatively synchronized with said indicator to hold said arm in a retracted position when said indicator is rotated away from its starting position but release said arm when said indicator is in its starting position, and means for rendering said arm inoperative when said indicator is rotated slightly opposite the direction for setting the same.

13. An interval timer comprising, a mounting, a motor, a time-measuring indicator journaled on said mounting for rotation through nearly a complete revolution from a starting position, multiple-speed gearing for connecting said indicator to said motor for operating said indicator at variable speeds for predetermined portions of its revolution, manual means for turning said indicator away from said starting position to set said gearing for effecting the desired operation of said indicator, a cam connected to rotate with said indicator and having an annular track of nearly 360 degrees terminating in a starting-point recess, a device controlling arm positioned adjacent said cam, and a cam-track follower on said arm engageable with said track when said indicator is rotated away from its starting point whereby said arm is held inoperative during the rotation of said indicator toward or away from said starting position but is released by the seating of said follower in said cam track recess when

said indicator returns to said starting position.

14. An interval timer comprising, a mounting, a motor, a time-measuring indicator journaled on said mounting for rotation through nearly a complete revolution from a starting position, multiple-speed gearing for connecting said indicator to said motor for operating said indicator at variable speeds for predetermined portions of its revolution, manual means for turning said indicator away from said starting position to set said gearing for effecting the desired operation of said indicator, a cam fixed on said shaft and having a cam track of nearly 360 degrees terminating in oppositely disposed radial off-sets, a signal-control arm hinged adjacent said cam, and a cam-track follower on said arm adapted to engage one of said off-sets to release a signal when said indicator is in its starting position but engage said track to cause said arm to hold said signal inactive when said indicator is moved away from its starting position, said cam follower being adapted to engage said other off-set to position said arm to hold said signal inactive when said indicator is rotated slightly in reverse of the direction in which it is moved for setting.

15. An interval timer comprising, a mounting, a motor, a time-measuring indicator journaled on said mounting for rotation through nearly a complete revolution from a starting position, multiple-speed gearing for connecting said indicator to said motor for operating said indicator at variable speeds for predetermined portions of its revolution, manual means for turning said indicator away from said starting position to set said gearing for effecting the desired operation of said indicator, a cam connected to rotate with said indicator and having an annular track of nearly 360 degrees terminating in a starting-point recess, a device-controlling arm positioned adjacent said cam, a cam-track follower on said arm engageable with said track when said indicator is rotated away from its starting point whereby said arm is held inoperative during the rotation of said indicator toward or away from said starting position but is released by the seating of said follower in said cam track recess when said indicator returns to said starting position, and coating shoulders on said mounting and said indicator adapted to limit the opposite rotating of said indicator.

16. An interval timer comprising, a mounting, an electric motor on said mounting, an electrically-actuated armature associated with said motor, a bracket on said mounting having a vibrator connected to said armature, an arm hinged on said bracket and movable into and out of position to immobilize said vibrator, a shaft journaled on said mounting for rotation toward and away from a starting position, a cam on said shaft having an annular cam track terminating in a radial offset, a cam-track follower on said arm engageable with said cam track to immobilize said vibrator when said shaft is turned away from said starting position and engageable with said offset to release said vibrator when said indicator is in its starting position, gearing connecting said shaft to said motor to effect the rotation of said shaft, and manual means for turning said shaft away from said starting position for setting said gearing to predetermine the amount of rotation of said shaft back to its starting position.

17. An interval timer comprising, a mounting, an electric motor on said mounting, an electrically-actuated armature associated with said

motor, a bracket on said mounting having a vibrator connected to said armature, an arm hinged on said bracket and movable into and out of position to immobilize said vibrator, a shaft journaled on said mounting for rotation toward and away from a starting position, a cam on said shaft having an annular cam track terminating in a radial offset, a cam-track follower on said arm engageable with said cam track to immobilize said vibrator when said shaft is turned away from said starting position and engageable with said offset to release said vibrator when said indicator is in its starting position, gearing driven by said motor, a pair of gears of differing diameter mounted on said shaft for meshing with said motor-driven gearing, and manual means for turning said shaft and selectively meshing said gears with said gearing so as to effect the operation of said indicator at variable speeds during predetermined portions of its revolution back to its starting position.

18. An interval timer comprising, a mounting, an electric motor on said mounting, an electrically-actuated armature associated with said motor, a bracket on said mounting having a vibrator connected to said armature, an arm hinged on said bracket and movable into and out of position to immobilize said vibrator, a shaft journaled on said mounting for rotation toward and away from a starting position, a cam on said shaft having an annular cam track terminating in a radial offset, a cam-track follower on said arm engageable with said cam track to immobilize said vibrator when said shaft is turned away from said starting position and engageable with said offset to release said vibrator when said indicator is in its starting position, gearing driven by said motor, a pair of circumferentially-spaced concentrically-arranged sector-shaped gears of differing diameters on said indicator, and manual means for turning said shaft and selectively meshing said gears with said gearing so as to effect the operation of said indicator at variable speeds during predetermined portions of its revolution back to its starting position.

19. An interval timer comprising, motor-driven gears, a time-measuring device having rotary movement, and gears of differing diameter on said device adapted to successively mesh with said driven gears for operating said device at variable speeds during predetermined portions of its rotary movement, certain of said gears having rounded teeth to permit forced slippage of said gears.

20. An interval timer comprising, motor-driven gears, a time-measuring device having rotary movement, and a pair of sector-shaped gears of differing diameters on said device adapted to successively mesh with said driven gears for operating said device at variable speeds during predetermined portions of its rotary movement, the teeth on said sector-shaped gears being of a relatively different slope from each other and from the teeth on said driven gears to permit forced slippage of said gears.

21. An interval timer comprising, motor-driven gears, a rotary time-measuring device mounted to permit a limited radial tilting of its axis, and a pair of sector-shaped gears mounted on said device and adapted to successively mesh with the respective gears of said pair of motor-driven gears for operating said device at variable speeds during predetermined portions of its rotary movement, the sum of the radii of one of said sector-shaped gears and one of said motor-

driven gears being sufficiently greater than the sum of the radii of the other said sector-shaped gear and the other motor-driven gear to effect a radially tilting of said device when said one sector-shaped gear and the respective motor-driven gear enter into or recede from meshing engagement and thereby avoid scraping of said other sector-shaped gear and its respective motor-driven gear.

22. In an interval timer, the combination of 10 a synchronous electric motor, driving gearing connected to said electric motor to rotate continuously therewith, a time measuring device, and a driven gear set connected with said time measuring device comprising gears of different diameters adapted to be meshed with said driving gears, said driven gear set comprising an idling gap in which said driving gearing normally has idling rotation.

23. In an interval timer, the combination of 20 a synchronous electric motor, driving gearing connected to said electric motor to rotate continuously therewith, a time measuring device, a driven gear set connected with said time measuring device comprising driven gears of different 25

5 diameters and an idling gap between two of such gears in which said driving gearing normally has idling rotation, and means for meshing said driven gears with said driving gearing for driving said time measuring device at different constant, uniform rates of speed, certain of said gears having rounded teeth to permit forced slippage of said gears.

WILLIAM P. GALLAGHER.
